UNITED STATES PATENT OFFICE

2,399,636

TOY

Keith Whitaker Johnson, Washington, D. C.

Application February 6, 1945, Serial No. 576,402

1 Claim. (Cl. 46—191)

My invention relates to improvements in toys, the principal object in view being to provide a simple form of inexpensive device for developing and arousing interest in children, more particularly, in passing a ball through a target, and which has the added advantage of producing a noise each time the ball passes through the target, which tends, especially where children are concerned, to encourage a player to develop a certain amount of skill with the toy.

Other and subordinate objects are also comprehended by my invention, all of which, together with the precise nature of my improvements, will be readily understood when the succeeding description and claim are read with reference to the drawings accompanying and forming part of this specification.

In said drawings:

Figure 1 is a view in front elevation of my improved toy in a preferred embodiment thereof,

Figure 2 is a view in longitudinal section taken on the line 2—2 of Figure 1,

Figure 3 is a view in front elevation of a modified embodiment of the invention,

Figure 4 is a view in longitudinal section taken on the line 4—4 of Figure 3, and

Figure 5 is a view in front elevation of a modified embodiment of noise-making device.

Referring to the drawings by numerals, and first to Figures 1 and 2, my improved toy, in the preferred embodiment illustrated, comprises a paddle 1 including a preferably flat handle 2, of suitable width to prevent the same from twisting in the hand, and an enlarged blade 3 with a preferably semi-circular outer end 4 and a circular opening 5 therein preferably concentric to said end 4 and forming the target. A cord 6, preferably of rubber, although not necessarily, is fixed at one end to the end 4 with a ball 7 on the other end, preferably of rubber, and sufficiently smaller than the opening 5 to be readily passed therethrough. The end of the cord 6 fixed to said end 4 is preferably tied, as at 8, in a transverse groove 9 in said end 4 preferably in the longitudinal center of the paddle 1 so that the fixed end of said cord will not creep along said end 4 but is free to slide around said end 4 when the ball 7 is passed through the opening 5. The blade 3, for amusement purposes, may be painted, stamped, or otherwise treated, on one or both sides, to simulate a grotesque head and face of which the opening 5 forms a wide open mouth. The paddle 1, for a purpose presently seen, is preferably, but not necessarily, formed of a pair of opposed, like sections 10, 11 of any light,

strong, inexpensive material, for instance, plastic.

A noise-making device is incorporated in the paddle 1, and which, in the preferred embodiment 5 of the invention, comprises an insert 12 of resilient, flexible material, such as Celluloid, or the like, preferably of the same shape and size as the paddle 1 and which is interposed between the sections 10, 11, said sections and the insert being 10 joined together in any suitable manner. The insert 12 is formed with spaced-apart tabs 13 extending into the opening 5 at one side thereof and forming upper teeth therein for the mouth simulated by said opening 5, said insert being also 15 provided with fins 14 opposite to tabs 13 spaced apart in the opening 5 upon opposite sides of the groove 9 and arranged to represent lower teeth in the mouth simulated by the opening 5. The spacing of the fins 14 provides for the cord 6 passing between said fins to opposite sides of 20 said opening 5. The fins 14 incline toward the space 14' between the same to cam the cord into said space when it is extended through the opening 5.

25 In using the described toy, the ball 7 is flipped back and forth by manipulation of the paddle 1 and jerked by the cord toward the paddle to pass the ball 7 through the opening 5. In its passage through said opening 5, the ball 7 flexes the tabs 13 and fins 14 and impacts the same with a noise effect resembling a snapping noise, and said tabs 13 and fins 14 react and reassume normal positions in the plane of the opening 5.

In the modified embodiment of my invention 35 illustrated in Figures 3 and 4, the paddle 15 is provided with a substantially annular enlarged end 16, and is formed in one piece. The noise-making device has the form of a disc 17 suitably fixed to one side of said end 16 and provided 40 with a substantially star-shaped opening 18 forming tapered fins 19 in the end 16 which function in the same manner as the tabs 13 and fins 14, as regards noise effect. The opening 18 is extended through the disc 17 between two adjoining fins 19 to the edge of the disc 17 in line with a groove 20 in said end 16, corresponding in function to the groove 9 of the preferred embodiment of the invention, and to form a space 18' between said fins corresponding in function to the space 14'. Thus, provision is made for the cord 21 passing through the end 16 of the paddle 15 from side to side thereof.

In the modified embodiment of the invention shown in Figure 5, the noise-making device has 55 the form of a disc 22 similar to disc 17 but pro-

vided with elongated tabs 23, some of different lengths than others, grouped part way around the opening 24 in said disc, said opening being extended through to the edge of the disc 22 to provide a space 24' for the same purpose as described with reference to the disc 17. The disc 22 is designed to be used in lieu of the disc 17 to produce a less audible sound effect.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claim.

What I claim is:

In a toy, a paddle provided with a target-form-

ing circular opening in one end thereof, a cord attached at one end to said paddle adjacent said opening, a ball on the other end of said cord smaller than said opening and adapted to be flipped through the opening from side to side of the same by manipulation of the paddle to exert a pull on the cord, and noise-making means in said opening yieldingly obstructing passage of the ball through said opening to produce a sound effect, said noise-making device comprising spaced-apart tabs on one side of said opening, and a pair of fins on the opposite side of said opening, said tabs and fins being of resilient flexible material and said fins being spaced apart to permit the cord to pass between the same as the ball is flipped from side to side of said opening.

KEITH WHITAKER JOHNSON.
